UNITED STATES PATENT OFFICE

2,487,836

ADJUSTABLE PITCH PROPELLER

Frederick W. Turnbull, Vienna, Va.

Application October 10, 1945, Serial No. 621,632

12 Claims. (Cl. 170—160.3)

(Granted under the act of March 3, 1883, as
amended April 30, 1928; 370 O. G. 757)

1

This invention relates to an adjustable pitch propeller with suitable controls associated therewith, and more particularly to a propeller of the screw type having blades which are rotatably adjustable as desired for altering the pitch thereof, as well as for completely reversing the pitch of the blades for obtaining astern motion of a vessel.

According to the improvements set forth herein, a propeller hub is illustrated which is driven by means of a hollow propeller shaft through which passes an inner shaft and within which said inner shaft is suitably mounted. The inner shaft is so associated with the propeller shaft that it rotates therewith during normal operation, but is adapted to be, by means of a suitable source of power, rotated relatively to said propeller shaft when required for blade adjustment and release of the propeller blade clutch.

With the blade or blades there is included a control flap portion, which flap is mounted preferably along and forming part of the trailing edge of the blade. The flap portion is controlled and actuated by means of the inner shaft and a system of connected gears associated therewith. As soon as the flap has been adjusted to the desired position, a clutch associated with each propeller blade is released to allow the opposing reaction caused by the water through which each blade and control flap are moving to cause the blades to be moved to their predetermined final position. The lag between the setting of the flap and the clutch release is conveniently accomplished by means of a lost motion or back-lash device in the gearing system. After the adjustment has been accomplished as outlined, the clutch reengages with the base of the blade to secure the blade in the final adjusted position.

From the above description it is apparent that the clutch does not release the blade for movement until the maximum torque is exerted by the flap. Retrogression of the blade to its original position can only be accomplished by the reversing of the flap and blade controlling mechanism, which first sets the flap to produce a retrogressing torque, then releases the clutch in the opposite sense from the release action described above.

Although the control flap portion, the clutch and the blade are illustrated as a compact unit, it will be appreciated that they may be operated independently of each other.

In addition to being adapted to release the clutch, it will be noted that the gearing will positively and independently rotate the blade where

substantial adjustment thereof is required. As shown in the illustrated embodiment, a relatively simple and rugged mechanical adjusting means is provided. Further, it is to be appreciated that the substitution of hydraulic, pneumatic or electric drives are contemplated to be within the scope of the improvements as described and claimed herein. A positively controlled adjustable pitch propeller is herein provided which may be released so that proper adjustment thereof from the controls of the ship can be made in accordance with any desired plan.

As illustrated in a prior patent issued to A. Flettner, Number 1,556,012 and dated October 6, 1925, the use of flaps or "governing surfaces," which when disposed at an angle to the blade surface will cause the current flowing along the blade to exert pressures differing from one another, is known. It is stated in the patent that this reaction will cause the blade to be turned until it has adjusted itself to the position of equilibrium corresponding to the direction of rotation and to the number of revolutions which may be made by this screw in each individual case. Unlike the present invention, the propeller of the patent is free at all times thereby subjecting it to a "hunting" action causing departure and adjusting procedure to take place constantly.

An object of this invention is to provide an adjustable pitch propeller in which the amount of pitch to which the propeller is subjected is adjusted by a flap portion mounted on the propeller blade or by positive driving means, or by the one in aid of the other.

Another object is to provide a current responsive propeller adjusting member which can be set in any one of an infinite number of predetermined positions, such adjustment being made from inside of the vessel on which it is mounted.

A further object of the invention is to provide a propeller blade clutch mechanism and means associated therewith for positively driving the propeller blades to adjust the pitch.

These, as well as the various other novel features and advantages of this invention will become apparent from a reading of the specification and accompanying drawings of which:

Figure 1 is a side elevational view, with parts broken away, showing the arrangement of the drive, clutch and propeller blades.

Figure 2 is an end view of the propeller hub having one blade mounted therein and a control flap associated therewith.

Figure 3 is a plan view, partly in section, of the clutch for securing the blade.

Figures 4 through 11 are diagrammatic views of a cross section of the propeller blade showing the various steps attained during adjustment.

With respect to the drawings, Figures 1 and 2 illustrate a propeller shaft 10 adapted to be driven in a clockwise or counter-clockwise direction through gear 11 from a primary source of power (not shown). Shaft 10 is made for the sake of illustration integral with its hub portion 12 within which are rotatably mounted adjustable propeller blades 13. A reversing motor such as direct current motor 14 and shaft 15 rotates bodily with shaft 10, four slip rings 16 through 19 of motor 14 are connected for sliding contact with brushes 20 through 23 respectively, and the direction of rotation of the motor is determined by having secured to the leads a switch mechanism and source of power (not shown).

The motor shaft 15 is provided with a gear 24 keyed thereto for driving the inner shaft 25, which gear meshes with the planetary gears in order to drive said inner shaft through studs 26 and 27. Suitable bearings 28 and 29 are spaced along the shaft 10 to support the inner shaft 25. A portion at the end of shaft 25 has mounted thereon gears 30 and 31, which gears engage co-operating bevel gears 32 and 33 of the propeller blade 13. A slot 34 provided on gear 30 engages a projection 35 of shaft 25. This combination of slot and projection constitutes a lost motion or back-lash device as will be more fully explained hereinafter. In normal operation of a ship, as a hub portion 12 and blades 13 are turned, there will be no driving or relative motion between sets of gears 30—32 and 31—33.

For securing the propeller blades 13 to the hub, plates 36 are provided which plates in turn are fastened to the hub by screws 37. All blades as illustrated are similarly mounted and driven, like numerals being given to like parts thereof. It is to be understood that two, three, four or more blades as desired may be employed in combination with the invention described herein.

In accordance with Fig. 1 gears 30 and 31 are constantly in engagement with gears 32 and 33, respectively. When the motor 14 is actuated, gear 31 causes gear 33 to be driven so that the control flap 38 is operated through a flexible cable 39. Cable 39 is secured at one end to gear 40, engaging with gear 41 mounted directly behind gear 33 on gudgeon 42, and at the other end to shaft 44 of the control flap 38. After the flap 38 is moved, the clutch 45 is disengaged, thereby releasing the elements so that the desired adjustment can be completed. This disengagement is accomplished in the illustrated embodiment by projection 35 turning gear 30, which in turn operates gear 32. The projections 46 or 47, mounted on gear 32 push one of each set of balls 48 in the direction of rotation. The other ball is pushed in the direction of rotation by spring 51.

With reference to Figure 3, it will be seen that the gear 30 may be used as an aid for adjusting the flap or for making the desired adjustment of the blade independently of the flap. The clutch illustrated is a simple type and yet most effective in operation. The housing for the clutch is anular and contains the ball members 48 and spring 51 which wedge the balls between the housing and cam surfaces on the stub of the blade. The housing is formed by the hub and the propeller stub end. There are several pairs of projections 46 and 47 on gear 32 which protrude into the clutch housing. Movement of the gear 75

32 will, in accordance therewith, move the wedge ball members 48 for releasing the clutch for response to pressures caused by the control flap. In addition, lugs 50 provided on the stub of the propeller blade may be positively moved by those projections 46 or 47 which are not in engagement with the clutch ball members 48.

The clutch of Figure 3 being mechanically symmetrical about its axis is obviously driven with equal ease in either direction, yet positively prevents the driven member being turned backward with relation to the driving member, since the ball elements, which are not held disengaged by the driving element, are kept constantly in place by spring 51 to prevent such movement by wedging between the hub and the stub of the blade. It is also to be noted that the driven element can progress only at the same speed as the driving element. More rapid movement will release the ball from the disengaging force and it will be pressed into clutching position by spring 51 so that the balls are wedged between the hub and the blade stub.

In accordance with Figures 4 through 7, the hub is illustrated as being driven in a clockwise direction when viewed from the left. The blade rotating with the hub is first shown as having no pitch whatsoever. In Figure 5, a control flap is illustrated as having been rotated out of line with the propeller blade edge. This places a clockwise twist on the blade when viewed toward the hub. If the clutch is released, the blade will tend to progress to the position shown in Figure 6, when the clutch is again engaged to secure the blade in the adjusted position. Thereupon the control flap is returned into alignment with the blade so that the vessel will be propelled in an astern direction.

When the propeller is not in rotation, adjustment of the blade will be had by the cooperating action of the gears 30 and 32 together with the clutch 45.

Also as illustrated in Figures 8 through 11 when the blade is in a certain position, the control flap 45 will have little or no adjusting effect. In such cases adjustment will be made independently of the flap as above described. When the propeller is employed with a reversing engine, the blades may be rotated 180° for affecting astern motion thereby presenting a propeller having the same identical characteristics which are inherent in the propeller when motion is in a forward direction.

The invention described herein may be made and used by or for the Government of the United States for governmental purposes without the payment to me of any royalties thereon or therefor.

What is claimed is:

1. An adjustable pitch propeller, comprising a drive shaft, a hub secured to said shaft, a propeller blade rotatably supported by said hub, a clutch within said hub between said blade and hub, and a gear rotatably mounted on said blade for driving said propeller blade through said clutch, said clutch comprising a runway formed by the converging walls of the blade and hub, a ball movable in said runway, a spring normally urging said ball into wedged contact with said converging runway walls, and a ball releasing device connected to said gear whereby said clutch may be released and said blade rotated relative to said hub.

2. An adjustable pitch propeller comprising a drive shaft having a propeller hub, a propeller

blade supported within and adapted to be rotated relative to said hub, a control flap adjustably secured to said blade, means to adjust the flap and a clutch operated by the flap adjusting means for locking and releasing said blade with relation to said hub.

3. An adjustable pitch propeller comprising a drive shaft having a propeller hub, a propeller blade supported within and adapted to be rotated relative to said hub, a control flap adjustably secured to said blade, actuating means for adjusting said flap and for rotating said propeller blade to augment the action of said control flap, said actuation means including a clutch for locking and releasing said blade with relation to said hub.

4. An adjustable pitch propeller comprising a drive shaft, a hub secured to said shaft, a propeller blade adjustably supported by said hub, a control flap secured to said propeller blade, a clutch for locking and releasing said blade with respect to said hub, means for rotating said flap to a predetermined position relative to said blade, said last mentioned means including a single drive shaft adapted to actuate said clutch as desired.

5. An adjustable pitch propeller comprising a drive shaft, a hub secured to said shaft, a propeller blade adjustably supported by said hub, a clutch within said hub for locking said propeller blade to said hub, means independent of such clutch to produce an adjusting force on said propeller blade, and control means, comprising means for positively rotating said propeller blades relatively to said hub and actuating said blade force adjusting means.

6. An adjustable pitch propeller comprising a drive shaft, a hub secured to said shaft, a propeller blade adjustably supported by said hub, a clutch operable in either direction within said hub for locking said propeller blade to said hub, means to produce a primary adjusting force on said propeller blade, means to release said clutch, said releasing means providing a secondary adjusting force to aid in adjusting said blade, and single means for actuating both said primary and secondary force adjusting means.

7. An adjustable pitch propeller comprising a drive shaft, a hub secured to said shaft, a propeller blade adjustably supported by said hub, means utilizing the action of the medium in which propeller is operating to exert an adjusting torque on said blade, a clutch for locking and releasing said blade with respect to said hub and a common driving element to actuate both said means and release said clutch in sequence.

8. An adjustable pitch propeller comprising a drive shaft, a hub secured to said shaft, a propeller blade adjustably supported by said hub, a clutch within said hub for locking said propeller blade to said hub, clutch control means comprising means for positively rotating said propeller blade relatively to said hub and additional means operated by said clutch control means, for pre-stressing the blade with a torque, to aid in adjusting said blade.

9. An adjustable pitch propeller comprising a drive shaft, a hub secured to said shaft, a plurality of propeller blades adjustably supported by said hub, means utilizing the action of the medium in which the propeller is operating to exert an adjusting torque on each of said blades, a clutch mounted on each blade for locking and releasing said blades with respect to said hub and a common driving element to actuate said means and said clutches as desired.

10. The device in claim 9 in which the said driving element comprises means interconnecting all of the blades so that each blade is adjusted at the same pitch angle as all of the other blades.

11. An adjustable pitch propeller comprising a drive shaft, a hub secured to said shaft, a propeller blade supported for rotation relative to said hub, a clutch within said hub between said hub and the root of said blade, releasably holding said blade against said rotation, and clutch operating means rotatably mounted on said blade for driving said propeller blade through said clutch.

12. An adjustable pitch propeller comprising a hub, a propeller blade rotatably supported by said hub, a driving means rotatably mounted on said blade for rotating said blade with respect to said hub, and a device to clutch said hub to said blade and to rotate said blade in said hub, selectively operable in either direction by rotation of the driving means with respect to the blade to adjust the pitch of said blade.

FREDERICK W. TURNBULL.
